[57] CLAIM

The design for a changing tray for infants, substantially as shown and described.

DESCRIPTION

FIG. 1 is a perspective view of a changing tray for infants showing my new design;

FIG. 2 is a rear elevational view thereof;

FIG. 3 is a left end elevational view thereof;

FIG. 4 is a bottom plan view thereof;

FIG. 5 is a perspective view of a second embodiment of a changing tray for infants showing my new design; and

FIG. 6 is a bottom plan view thereof.
